UNITED STATES PATENT OFFICE.

AUSTIN F. JACKSON, OF TAUNTON, MASSACHUSETTS.

DESIGN FOR A BACK FOR BRUSHES.

SPECIFICATION forming part of Design No. 27,204, dated June 15, 1897.

Application filed April 22, 1897. Serial No. 633,407. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Backs of Hair-Brushes, &c., of which the following is a specification, reference being had to the accompanying drawings, showing a part thereof.

My invention is in the nature of a new design for the backs of hair, cloth, and hat brushes, hand-mirrors, and other like articles.

Figure 1 is a view of the back of a hair-brush or mirror embodying my design. Fig. 2 is a side view of a hair-brush, and Fig. 3 a cross-section through the back.

The leading feature of my design is an oval-shaped back A, having creases or waves running longitudinally to the same and with two reversely-curved bands *a a* also running longitudinally in general direction and having their convex faces adjacent to each other. These bands are in relief and have the appearance of a series of beads or balls increasing in size from the middle outwardly and terminating in scrolls *a'* at each end and having a central raised ornament *a²* in the middle.

The handle B of the brush or mirror appears waved, as seen in Fig. 2, and near its end has, as seen in Fig. 1, a terminal ornament in the form of symmetrical raised scrolls *a³*. The handle of the brush may, however, be omitted and the back of the brush may terminate at the dotted line *x* and may be made of somewhat longer proportion as compared with its width, as when applied to what is known as "hat," "cloth," or "military" brushes.

Having thus described my invention, what I claim is—

1. The design for the back of a brush or like article comprising the body portion A and handle portion B as shown and described.
2. The design for the back of a brush or like article comprising the body portion A as shown and described.
3. In a design for the back of a brush or like article the handle portion B as shown and described.

AUSTIN F. JACKSON.
